UNITED STATES PATENT OFFICE.

DANIEL A. LOESER, OF SAG HARBOR, NEW YORK.

DESIGN FOR A SPOON OR FORK HANDLE.

SPECIFICATION forming part of Design No. 28,022, dated December 14, 1897.

Application filed October 5, 1897. Serial No. 654,187. Term of patent 7 years.

To all whom it may concern:

Be it known that I, DANIEL A. LOESER, a subject of the Emperor of Germany, residing at Sag Harbor, in the county of Suffolk and State of New York, have invented and produced a new and original Design for Spoon or Fork Handles, of which the following is a specification, reference being had to the accompanying drawings, which show, in—

10 Figure 1 shows the obverse side of a spoon or fork handle, and Fig. 2 the reverse side, the tines of the fork being shown in dotted lines.

The leading or characteristic feature of my design consists of beaded decoration on the 15 face and near the edge of the handle, the beads being elongated and separated by small circular beads, both the elongated and circular beads increasing in size toward the outer end of the handle, where they meet a fanciful

scroll, the lower end of the handle being also 20 decorated with a fanciful scroll.

Referring to the drawings, A represents the obverse side of a spoon or fork handle, and B the reverse side thereof. On the face A and near the outer edge thereof the handle is 25 provided with a beaded decoration, the beads *a* being elongated and separated by smaller circular beads *c*, said beads increasing in size from the scroll *e* at the lower end of the handle toward the outer end of the handle, which 30 is decorated with a fanciful scroll *d*.

What I claim is—

The design for a spoon or fork handle substantially as herein shown and described.

DANIEL A. LOESER.
